UNITED STATES PATENT OFFICE.

MOSES E. NICHOLS, OF CLARKSVILLE, MISSOURI.

DESIGN FOR BOOT-JACKS.

Specification forming part of Design No. 7,633, dated August 11, 1874; application filed July 25, 1874.
[Term of Patent 7 years.]

To all whom it may concern:

Be it known that I, MOSES E. NICHOLS, of Clarksville, Pike county, Missouri, have invented a new and Improved Design for Boot-Jack, of which the following is a specification:

The nature of my design for a boot-jack is fully represented in the accompanying photographic illustration, to which reference is made.

The said design consists in a boot-jack made in the form of a human body, whereof the main portion of the jack is in the form of body A, head B, and the arms C, and the prongs are made in the form of the legs D, the arms being disposed as if the hands were clasped

together behind the head, and the legs being elevated or inclined forward from the hips to the knees, and extended or spread apart from the hips to the feet.

I claim as new and desire to secure by Letters Patent—

The design for a boot-jack, consisting of the form of a human figure, as set forth.

MOSES E. NICHOLS.
